(57) **CLAIM**

The ornamental design for a display screen with graphical user interface, as shown and described.

DESCRIPTION

FIG. 1 is a front view of a display screen with graphical user interface; and,

FIG. 2 is a second embodiment thereof.

The graphical user interface includes a symbolic break in a portion of the interface. The appearance of the graphical user interface between the break lines forms no part of the claimed design.

The broken lines showing a display screen and elements of the graphical user interface illustrate portions of the article, and form no part of the claimed design.
